WHEEL FOR RAILWAY VEHICLES

Gustav F. de Buigné, Vienna, Austria

Application February 14, 1934, Serial No. 711,269
In Austria February 20, 1933

5 Claims. (Cl. 105—165)

The disadvantages of the wheels of railway vehicles heretofore in use are well known. These wheels have conical running surfaces the generatrices of which located at the contact point with the rail are inclined upwards away from the vertical central plane of the track. These wheels tend to grooving the rails and to self-derailments. It has already been proposed to do away with these drawbacks by so shaping the running surfaces of the wheels that they are conical but that their generatrices at the contact point with the rails are inclined upwards towards the central vertical plane of the track. But these wheels have not been adapted because in the absence of the wheel flanges the safe running of the vehicles appeared endangered although such wheels automatically corrected the position of the axle. Such wheels did not permit of making wheel bodies with rocking axles or with a differential drive since the danger of derailment could not be perfectly done away with. Providing outer flanges was prohibited since it would have necessitated a change of the construction of the entire permanent way. Now the invention makes it possible to so alter in the simplest manner wheels with inner flanges heretofore used that they show all the advantages of wheels having conical running surfaces the generatrices of which at the point of contact with the rails are inclined upwards towards the vertical central plane of the track without their disadvantages. A differential drive of rocking axles is made possible by the invention without necessitating a change in the existing permanent way.

According to the invention these results are obtained by providing each wheel of a set of wheels with a guiding rib of low height cooperating with the outside of the rail head. This guiding rib merges in continuous curvature into a surface of revolution diminishing in diameter towards the vertical central plane of the track, the said surface of revolution making, as seen in transverse section, an acute angle with the horizontal running surface of the rail head. It is particularly advantageous to construct the said surface of revolution as a conical surface the bottom generatrices of which are inclined upwards towards the vertical central plane of the track. In case of wheels inclined to the vertical, however, the said surface of revolution may be constructed as a cylindrical surface of corresponding inclination. Independently thereof in such wheels the standard inner flange may be provided and parts of the running surfaces

may even be provided with cones, the bottom generatrices of which are inclined upwards away from the vertical central plane of the track. For grooved rails and hence more particularly for tramway wheels the invention may be simply made suitable by causing the guiding rib to cooperate with the outer surface of the inner part of the rail head and causing the conical surface the bottom generatrices of which are inclined upwards towards the vertical central plane of the track to cooperate likewise with the said inner part of the rail head.

With the conventional railway wheels, i. e. those with a tread inclined upwardly and away from the central vertical plane of the track, an attempt to position the wheels so that their axle is at right angles to the axis of the track will result in the wheels seeking to turn so that their axle makes an acute angle with a normal to the track, in a horizontal plane. This movement is due to the fact that under the influence of gravity, the pair of wheels always seek a position of smallest possible radius, the radius of the circle on which the contacting points in the first case lie being greater than that of the circle on which lie the contacting points in the second case. Thus with the wheels now in use, a tendency for derailment is present.

The contrary effect takes place in the case of my invention. When my wheels are positioned on the tracks with their axle at right angles to the longitudinal axis of the tracks, they will retain their right-angular relation, and will even assume that position if they are initially set at an angular relation with respect to the tracks. This tendency is also due to the effect of gravity.

The differences between the conventional and my construction are particularly emphasized when the wheels traverse curves. In the case according to the conventional design, friction will occur between the wheel and the track on the inside of the outer rail, so that the pair of wheels is turned in a direction opposite to that necessary for correct running on the curve. In my case, on the contrary, when the wheels run into a curve, friction occurs between the inner wheel and the outside of the inner rail, so that pivoting about this point of contact as a center, the wheels are turned automatically into their correct position for running in the curve.

In the drawing some constructional forms of the subject matter of the invention are shown diagrammatically by way of example.

Fig. 1 shows in transverse section the head of a Vignole rail together with a corresponding wheel tire. Fig. 2 is a similar view of a Vignole rail head cooperating with a divided wheel tire. Fig. 3 is a similar view of the head of a grooved rail and a corresponding wheel. Fig. 4 is a similar view of a grooved rail with a divided wheel tire. Fig. 5 shows a set of wheels with horizontally rocking axles. Fig. 6 shows a 10 horizontally rocking set of wheels with wheels inclined to the vertical. Fig. 7 shows a set of wheels with horizontally and vertically rocking axles. Fig. 8 shows a set of wheels with steering 15 wheels.

15 The head 1 of the Vignole rail (Fig. 1) is in transverse section exactly the same as heretofore. The wheel is provided according to the invention at its outside with a guide rib 3 projecting only slightly. The guide rib only projects approximately so far below the top of the rail as the curvature of the running surface of the head of the rail extends, that is to say, until the curved outline of the transverse section merges into the vertical. This guide rib 20 3 merges by a continuously curved outline 4 into an outwardly opening core 5 which can extend either over the entire running surface of the wheel or it can extend to about the top of the rail, that is to say, up to the point 6. At the 25 inner side of the wheel there is provided the usual flange 7.

30 The guide rib provided according to the invention and projecting only slightly below the top of the rail makes it possible that the wheel can run without shocks over switches, crossings, and the like without necessitating any change of these parts. On the other hand the guide rib secures all the advantages warrented by an outer flange projecting to a much greater extent.

35 40 The shockless passing of switches and crossings can be enhanced by yieldingly mounting the guide rib 3 in a circumferential groove 15 of the wheel, as shown in Fig. 2, it being advantageous to insert between the guide rib 3' and the bottom of the groove resilient elements such as 45 springs, rubber or the like. The effect of this arrangement is that in normal running the guide rib is caused to contribute to the desired correction of the movement of the wheel, while on 50 passing switches or curves the guide rib retires into the groove 15 against the action of the resilient elements 16.

55 In the constructional form of the invention shown in Fig. 3 and designed for grooved rails the latter may be used in their normal size and shape, but in this case the guide rib runs in the groove of the rail and cooperates with the outer side 10 of the inner part 11 of the head of the grooved rail. The transverse section of this 60 guide rib merges by a continuous curve into a conical surface 12 the bottom generatrices of which are inclined upwards towards the central vertical plane of the track. This conical surface cooperates with the running surface of the inner part 11 of the head of the grooved rail. In this case no change whatever in the permanent way is necessary, since the guide rib serves 65 as a substitute for the normal flange. All the guiding functions performed in ordinary rail-ways by the outer guide rib and the head of the Vignole rail are performed, in the present case by the inner part 11 of the head of the grooved rail, the guide rib 3 and the cone 12 while the normal outer running surface 13 of 70 the wheel takes up the major part of the load.

In this construction too the friction conditions may be rendered more favorable if the tire is divided along a plane perpendicular to the axle, as shown in Fig. 4, so that the guide rib together with the conical running surface is arranged on one part 12' of the wheel while the load supporting tire and the outer running surface 13 are arranged in the other part 12' of the wheel which may also be provided with a guide rib, as is indicated in broken lines.

The wheel parts 12' and 13' may be provided with separate supporting springs.

The particular inclination of the running surface of the wheels to the running surface of the rail contributes to the automatic correction of the adjustment of the axle primarily due to the guide rib. In consequence thereof the invention permits to so construct sets of wheels with independently driven wheels with rocking axles and finally with steering axles.

Fig. 5 shows a set of wheels consisting of wheels with conical running surfaces constructed in accordance with the invention in which each wheel 17, 18 is separately journalled in a journal pin of a through-going wheel axle 19 so that this axle may be mounted free to rock on a vertical pivot 21. 22 are the usual supporting springs. Notwithstanding the provision of a rocking axle a derailment of the set of wheels is impossible owing to the special construction of the wheels.

The constructional form illustrated by Fig. 6 shows the same construction of the axle as the constructional form just described with the sole difference that the planes of the wheels are inclined to the vertical and their journal pins are correspondingly inclined to the horizontal. This construction of the wheel axles permits to use wheels with a cylindrical running surface instead of such with a conical running surface 4 the bottom generatrices of which are inclined upwards towards the central vertical plane of the track. The inclination of the wheels secures the same advantage as the conical running surface of inverted inclination.

In the constructional form shown in Fig. 7 the wheels 17, 18 are journalled on half axles 19, 20 pivoted at 25 to a member 24 mounted on a journal pin 21 to rotate in a horizontal plane. The journal pin 21 is rigidly connected to a transverse spring 28 bearing from above against the half axles 19, 20. With this construction the wheels are adapted to rock not only in a horizontal plane but also in a vertical plane whereby a still more smooth running of the set of wheels is secured.

The constructional form illustrated in Fig. 8 shows wheels 17, 18 mounted on journal pins 27, 28, vertical pivots 29 being provided at the inner ends of the said journal pins. The pivots 29 are 60 connected by a yoke 30. The journal pins 27, 28 are connected with each other by levers 31 journalled on the pivots 29 and a link 32.

The construction of the running surface of the wheels makes it possible, as is seen from the 65 above, to employ them in various constructions of the drive, since owing to the construction of the wheels an automatic correction of the running of the wheel is brought about, but not a tendency to derailment is set up.

What I claim is:

1. In a vehicle running on rails constituting a track and having a frame, at least one axle supporting said frame and prevented from revolving around its longitudinal axis in said frame,

- said axle having journals at both of its ends, a wheel on each of said journals and each freely revolvable thereon independently of the other, the periphery of each of said wheels comprising a tread part and a guide rib at that end of said tread part more remote from the vertical central plane of said track, the generatrix of said tread being substantially rectilinear and said generatrix, at its point of contact with the associated rail, being inclined upwardly towards the central vertical plane of said track, and means securing said axle to said frame in such manner as to permit said axle to rock around a vertical axis.
- 5 2. In a vehicle running on rails constituting a track and having a frame, at least one axle supporting said frame and prevented from revolving round its longitudinal axis in said frame, said axle having journals at both of its ends, said journals being inclined upwardly and towards the central vertical plane of said track, a wheel on each of said journals and freely revolvable thereon independently of the other, the periphery of each of said wheels comprising a tread 10 part and a guide rib at that end of said tread part more remote from the vertical central plane of said track, the generatrix of said tread being substantially rectilinear, and said generatrix, at its point of contact with the associated rail, being inclined upwardly and towards the central vertical plane of said track, the said rail having a circumferential groove therein, at the outside of said wheel, the said guide rib being radially yieldingly mounted in said circumferential 15 groove of said wheel and normally projecting slightly beyond said tread, and means securing said axle to said frame in such manner as to permit said axle to rock around a vertical axis.
- 15 3. In a vehicle running on rails constituting a track and having a frame, at least one axle supporting said frame and prevented from revolving round its longitudinal axis in said frame, said axle comprising a central support portion, an end portion at each end, each said end portions 20 carrying and being journaled to said central portion by a horizontal journal pin extending parallel to the central vertical plane of the track and said central portion of the axle being journaled on a vertical journal pin located substantially in the central vertical plane of said track, a wheel carried by each of said end portions at its outer extremity, said wheel being freely revolvable independently of each other, the periphery of each of said wheels comprising a tread 25 part and a guide rib at that end of said tread part more remote from the vertical central plane of said track, the generatrix of said tread being substantially rectilinear and said generatrix, at its point of contact with the associated rail being 30 inclined upwardly and towards the central vertical plane of said track relatively to said longitudinal axis of said axle, and securing said axle to said frame in such manner as to permit said axle to rock around a vertical axis.
- 20 4. In a vehicle running on rails constituting a track, and having a frame, at least one axle supporting said frame and prevented from revolving round its longitudinal axis in said frame, said axle having journals at both of its ends, a wheel on each of said journals and freely revolvable thereon independently of the other, the periphery of each of said wheels comprising a tread 35 part and a guide rib at that end of said tread part more remote from the vertical central plane of said track, the generatrix of said tread being substantially rectilinear, and said generatrix, at its point of contact with the associated rail, being inclined upwardly and towards the central vertical plane of said track, the said rail having a circumferential groove therein, at the outside of said wheel, the said guide rib being radially yieldingly mounted in said circumferential 40 groove of said wheel and normally projecting slightly beyond said tread, and means securing said axle to said frame in such manner as to permit said axle to rock around a vertical axis.
- 25 5. In a vehicle running on rails constituting a track and having a frame, at least one axle supporting said frame and prevented from revolving round its longitudinal axis in said frame, said axle comprising a central support portion, an end portion at each end, each said end portions 45 carrying and being journaled to said central portion by a horizontal journal pin extending parallel to the central vertical plane of the track and said central portion of the axle being journaled on a vertical journal pin located substantially in the central vertical plane of said track, a wheel carried by each of said end portions at its outer extremity, said wheel being freely revolvable independently of each other, the periphery of each of said wheels comprising a tread 50 part and a guide rib at that end of said tread part more remote from the vertical central plane of said track, the generatrix of said tread being substantially rectilinear and said generatrix, at its point of contact with the associated rail being inclined upwardly and towards the central vertical plane of said track relatively to said longitudinal axis of said axle, and securing said axle to said frame in such manner as to permit said axle to rock around a vertical axis.

GUSTAV FR. DE BUIGNÉ.
